(57) **CLAIM**

The ornamental design for shoot rest, shown and described.

DESCRIPTION

FIG. 1 is a perspective front view of a shooting rest, showing our new design;

FIG. 2 is a perspective back view thereof;

FIG. 3 is a top view thereof;

FIG. 4 is a front view thereof;

FIG. 5 is a back view thereof;

FIG. 6 is a bottom view thereof;

FIG. 7 is a right view thereof; and,

FIG. 8 is a left view thereof.

The broken line showing of fasteners and recesses is included for the purpose of illustrating portions of the shooting rest that forms no part of the claimed design.
